UNITED STATES PATENT OFFICE.

LESLIE D. WHITNEY, OF SAN FRANCISCO, CALIFORNIA.

HYDRAULIC PRESS.

Application filed August 28, 1922. Serial No. 584,653.

To all whom it may concern:

Be it known that I, LESLIE D. WHITNEY, a citizen of the United States, residing at the city and county of San Francisco and 5 State of California, have invented certain new and useful Improvements in Hydraulic Presses, of which the following is a specification.

My invention relates to the class of hydraulic presses especially adapted for compressing granular or finely divided material, such, for example, as common salt, into small, hard cakes.

The object of my invention is to provide 15 an apparatus of the described class which is simple in construction and rapid and efficient in operation. To this end I employ a plurality of molds, so mounted as to be successively brought into the spheres of action 20 first of the compressing mechanism, and then of the ejecting mechanism, said compressing and ejecting mechanisms operating simultaneously upon successive molds.

My invention will now be fully described 25 with reference to the accompanying drawings, wherein—

Fig. 1 is a side elevation of my press, the fluid connections and control valve being omitted.

Fig. 2 is a plan view of the same.

Fig. 3 is a vertical section taken on the line 3—3 of Fig. 2, showing the fluid connections and controlling means.

Fig. 4 is a sectional plan view taken on the line 4—4 of Fig. 1.

In the drawings, the reference numeral 1 designates a base, from which rise a pair of fixed supporting columns 2 and 2' carrying a fixed head 3. This head has formed with- 40 in it a fluid pressure cylinder 4, closed at the top and open at the bottom. A piston 5—Fig. 3 operates vertically within said cylinder 4, and projects from its lower end through a suitable packing gland 6. Said 45 piston carries a cross head 7, to which is secured the upper or compressing die 8. The fixed head 3 also carries a second fluid pressure cylinder 9, above and preferably in vertical alignment with the cylinder 4. Said

50 second or upper cylinder 9 is smaller in diameter than the cylinder 4, and is inverted, being closed at its bottom. A piston 10 operates in the upper cylinder 9, projecting from its upper end through a packing gland 11. A cross head 12, Fig. 1, secured to said piston 10, carries two depending rods 13,

which slide freely in guide bearings 14 in the fixed head 3, and are secured at their lower ends to the cross head 7, as shown at 15. The pistons 5 and 10 are thus connected together, and move in unison.

Fluid, under suitable pressure is admitted continuously to the upper cylinder 9 through a connecting pipe 16, Fig. 3, from a suitable source, not shown, and normally maintains the upper die 8 in a position above that shown in the drawings. When the fluid, from the same source, is admitted to the lower cylinder 4 through a connection 17, and a three-way valve 18, the die 8 is 70 forced downward into the position shown, by reason of the difference in effective area of the two pistons 5 and 10; and when the pressure is relieved in the lower cylinder 4, by turning said valve 18 so that the supply 75 is cut off and the fluid in said cylinder 4 is allowed to escape through the discharge outlet 19, the die 8 is again elevated by the pressure in the upper cylinder 9. Thus the movement of said die 8 is controlled entirely 80 by the single valve 18. It should be understood, however, that the three-way valve 18 is herewith illustrated merely as a preferred means for controlling the movement of the die 8, and that any other similar or equivalent means for controlling the admission of the fluid to and its discharge from the cylinder 4 may be employed.

The mold in which the cakes are formed comprises a cylindrical bushing 20 carried 90 in a horizontal rotatable member or turret 21. There are preferably four such molds in said turret, as shown in Fig. 4, but more or less may be used as desired. The turret 21 is rotatably mounted upon the fixed 95 column 2', and, in the present instance, is intended to be rotated manually to bring the molds 20 successively in alignment with the die 8. A thrust collar 22, Fig. 3, is secured to the column 2' above the turret 21, and 100 said turret is normally pressed upward, against said collar, by a spring 23, which allows the turret to give, in a downward direction, in case it is not properly positioned when the die 8 descends.

105 A spider 24 is secured beneath the turret 21 and rotates therewith. Said spider carries spindles 25, upon the upper ends of which are formed or secured the lower or resisting dies 26. There is one such spindle 110 and die for each mold 20, the die normally occupying a position within the lower por-

tion of the mold, as shown at the left in Fig. 3. The spindles 25 are vertically slideable in the spider 24, and are held in their normal position by springs 27 and thrust collars 28. A fixed rest or foot 29 is mounted in the base 1, upon which the lower end of each spindle 25 rests when said spindle is in vertical alignment with the upper die 8, so that the thrust is taken by the base 1 rather than by the spider 24.

The slideable spindles 25 are employed to eject the formed cakes from the molds. For this purpose there is provided a bifurcated lever 30, Figs. 3 and 4, fulcrumed at 31 upon the base 1, and having one end connected by a pair of links 32 with the movable cross head 7 of the upper die 8. The other end of said lever 30 carries a roller 33, which is positioned beneath the lower end of the spindle 25 which is diametrically opposite to the spindle aligned with the upper die 8, as shown in Fig. 1 and at the right in Fig. 3. Thus when the compressing die 8 moves down, to compress the cake within the mold 20 at the position B in Figs. 3 and 4, the lever 30 causes the opposite spindle 25 to be elevated, as shown, thereby ejecting the formed cake from the mold 20 at the position C.

In the operation of the machine, the un-compressed material is placed in the mold 20 at the position A, Fig. 4, by hand or otherwise, and the turret 21 is rotated to bring the mold thus charged to the position B beneath the upper or compressing die 8. The valve 18, Fig. 3, is then turned to the position shown, to admit fluid to the lower cylinder 4, thereby forcing said die 8 downwardly and compressing the material, after which said valve is turned to permit the discharge of the fluid from said cylinder 4, allowing said die 8 to be elevated by the upper piston 10. In the meantime, a fresh charge of material has been placed in the following mold 20 at the position A. The turret 21 is then rotated a quarter turn, and the operation repeated. When the first mold 20 with the formed cake therein reaches the position C, the operation of the compressing die 8 at B elevates the spindle 25 at C, as shown in Fig. 3, thereby causing its resisting die 26 to eject the previously compressed cake from the mold.

I claim:—

1. A press comprising a fixed support; a rotatable member mounted thereon and provided with a mold; a reciprocative compressing die coacting with said mold from one side as the same is brought into registry therewith by the rotation of said member; a reciprocative resisting die carried by said rotatable member and adapted to coact with said mold from the other side; a fixed member carried by said support for holding said resisting die in functional compressing po-

sition relatively to said mold when the latter is in registry with the compressing die; and means for moving said resisting die to eject a previously compressed mold content when said mold is out of registry with the compressing die.

2. A press comprising a fixed support, a rotatable member mounted thereon and having a plurality of molds; a reciprocative compressing die coacting with said molds from one side as each is brought, by the rotation of said member, into registry successively therewith; a plurality of reciprocative resisting dies carried by said rotatable member, each coacting with its respective mold from the other side; a fixed member mounted on said support for holding said resisting dies in functional compressing position relatively to their molds when said molds are in registry with the compressing die; and means for moving said resisting dies when their molds are out of registry with said compression die, to eject a previously compressed content.

3. A press comprising a resiliently mounted rotatable member having a plurality of molds; a compressing die coacting with said molds from one side as each is brought, by the rotation of said member into registry successively therewith; means for reciprocating said compressing die; a plurality of reciprocative spindles carried by said rotatable member; a die carried by each spindle coacting with the molds from the other side; means independent of said rotatable member for acting on said spindles to hold their dies fixed in their molds when in registry with the compressing die; means acting on said spindles when their dies are out of registry with the compressing die to move said spindles and their dies to eject a previously compressed mold content; and connections between the reciprocating means of the compressing die, and the ejecting means of the resisting dies to operate the latter upon the compressing movement of the former.

4. A press comprising a rotatable member having a plurality of molds; a compressing die coacting with said molds from one side as they are brought successively into registry therewith, a reciprocative member carrying said compressing die; a plurality of reciprocative spindles carried by said rotatable member, each having a resisting die coacting with the respective molds from the other side; a fixed bearing acting on said spindles to hold their dies in fixed position in the molds when in registry with the compressing die, a pivoted lever bearing at one end under the spindles when their dies are out of registry with the compressing die, and adapted to move said dies to eject a previously compressed mold content; and rods directly connecting the other end of said lever with the reciprocative member of

the compressing die, and adapted to operate said lever for its ejecting function upon the compression movement of said compressing die.

5 5. A press comprising a rotatable resiliently mounted turret having a plurality of molds; a reciprocative piston carrying a compressing die adapted to coact with said molds from one side as each is brought into 10 registry therewith; a spider carried by said turret; a plurality of spindles resiliently slidable in said spider, each spindle having a resisting die coacting with a respective mold from the other side; a fixed bearing

acting on said spindles to hold their dies in 15 fixed position in the molds when in registry with the compressing die; a lever for moving the spindles when their dies are out of registry with said compressing die, to eject a previously compressed mold content; and 20 connections with the operating piston of the compressing die to operate the lever for its ejecting function upon the compressing movement of said piston.

In testimony whereof I have signed my 25 name to this specification.

LESLIE D. WHITNEY.
